CLAIM

The ornamental design for a switching handle, as shown and described.

DESCRIPTION

FIG. 1 is a perspective view of a switching handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view shown in a different environment; and,

FIG. 9 is another perspective view shown in a different environment.

The broken lines shown in FIG. 1, FIG. 6, and FIG. 7 represent portions of a switching handle and form no part of the claimed design.

The broken lines shown in FIG. 8 and FIG. 9 are for the purpose of illustrating environment and form no part of the claimed design.

1 Claim, 6 Drawing Sheets
